UNITED STATES PATENT OFFICE.

ELMER JNO. HINKSON, OF ERIE, PENNSYLVANIA.

AUTOMATIC GAS SHUT-OFF.

1,173,966.

Specification of Letters Patent. Patented Feb. 29, 1916.

Application filed July 22, 1914. Serial No. 852,517.

To all whom it may concern:

Be it known that I, ELMER J. HINKSON, a citizen of the United States, residing at Erie, in the county of Erie and State of Pennsylvania, have invented new and useful Improvements in Automatic Gas Shut-Offs, of which the following is a specification.

This invention is an improved automatic gas shutoff for use in a gas service pipe to close the same in the event that gas pressure should be materially reduced in the pipe and thereby avoid the danger resulting from material variations of gas pressure, the object of the invention being to provide an improved device of this character including in combination with a gas duct or service pipe a normally open cutoff valve therefor, a valve serving as a circuit closure normally open and held so by gas pressure and adapted to close upon a discontinuance of such pressure, normally inactive electrically operated means to close the cutoff valve, a normally open electric circuit in which said electrically operated means is included and circuit closing means operated by the valve serving as a circuit closure when the latter closes, as hereinafter described and claimed.

In the accompanying drawings:—Figure 1 is an elevation of an automatic gas cutoff apparatus constructed in accordance with my invention, the casing for the same being indicated in section. Fig. 2 is a vertical central sectional view of the same. Figs. 3 and 4 are detail views.

For the purposes of this specification a gas service pipe is indicated at 1.

In accordance with my invention I provide an aluminum cutoff valve 2 which is arranged in said pipe and which is normally open, but which may be moved so as to cut off flow of gas through the pipe. I also provide a valve 3 provided with circuit closing means, said valve being arranged in the service pipe and co-acting with a seat 4. This valve is held open by the pressure of gas in the direction indicated by the arrow in Fig. 1 and is provided with a pivot rod 5 which is mounted in bearings 6 and is provided at one end with an arm 7 which carries an electric contact point 8. The valve 3 although normally held open by gas pressure is adapted, upon discontinuance of gas pressure or a dangerous diminution thereof to close by its own gravity against the seat 4 and thereby raise the arm 7.

A frame 9 of suitable construction is at-

tached to the service pipe and is here shown as arranged in a suitable casing 10. This casing has a door 11. The core 12 of a solenoid is arranged vertically and depends from the upper side of the frame at a suitable distance from the pipe 11 and is provided with an arm 13 which has an electric contact point 14 adapted to coact with the point 8 but normally out of contact therewith. The coil 15 of the solenoid, which is adapted to move vertically on the core is provided on one side with a vertically arranged conducting strip 16 which has a shoulder 17 near its lower end. The coil also has a finger point 18 to enable it to be readily manually raised and the coil is further provided, at its lower end, with a stud 19. The cutoff valve is here shown as a plug valve and is provided with an arm 20 at one side which is provided with a contact point or device 21. A rod 22 is vertically arranged, has its lower end pivotally connected as at 23 to the valve arm 20 and is provided near its upper end with a slot 24 in which the stud 19 operates.

A conducting bar 25 is arranged on a support 26 and has a binding post 27. The frame 9 has an opening 28 through which extends a dog 29 the same being pivotally mounted as at 30 and its inner end being adapted to engage under the shoulder 17 so as to support the coil of the solenoid normally in elevated position. At the outer end of the dog is a counterbalancing weight 31. Its inner end, which normally supports the coil of the solenoid, normally rests on a contact point 32 which is connected by a conductor 33 to one pole 34 of an electric battery 35. The other pole 36 of the battery is connected by a conductor 37 to the binding post 27 and said binding post is also connected by a conductor 38 to the contact point or member 8. One end of the winding of the solenoid coil is connected by a conductor 39 to the contact point 14. The other end of the winding is connected by a conductor 40 to the conducting bar or strip 16. An electric audible alarm is connected by a conductor 42 to the contact point 21 and by a conductor 43 to the pole 34 of the battery. Normally the electric circuit is broken between points 8—14 and points 21—25, the valve 2 being held open by the coil 15 which latter is held in elevated position by the dog and the controlling valve 3 is held in open position.

In the event that there should be a discontinuance of gas pressure in the pipe 1, even if only momentarily, the valve 3 which serves as a circuit closure will close by its own gravity and thereby raise the arm 7. This causes the contact point 8 to come in electric contact with the point 14 and thereupon an electric current will pass from the pole 36 of the battery through the conductors 37 and 38, points 8—14, conductors 39, the winding of the coil 15, the conductor 40, conducting bar on strip 16 and through the dog, point 32 and conductor 33 back to the pole 34 of the battery. Hence the coil becomes energized and moves upwardly on the core 12 a sufficient distance to cause the shoulder 17 to clear the point of the dog, thereupon the weight 31 of the dog raises its point and releases the same from the shoulder 17, thereby breaking the electric circuit between the conductor 16 and the contact point 32 and permitting the coil to drop. The weight of the coil is thus imposed upon the arm 20 through the rod 22 and said arm is caused to close the cutoff valve, thus positively preventing flow of gas through the pipe 1. The contact point 21 of the arm 20 is brought into contact with the conducting bar 25 thus establishing an electric current from the pole 36 of the battery, through conductors 37 and 25 and 42, the signal 41 and back to the pole 34 of the battery and through the conductor 43 thus causing the signal to sound an alarm. The flow of gas through the pipe cannot be re-

established until after the device has been reset, by manually raising the coil 15 and reengaging the shoulder 17 with the point of the dog.

While I have herein shown and described a preferred form of my invention I would have it understood that changes may be made in the form, proportion and construction of the several parts without departing from the spirit of the invention and within the scope of the appended claim.

Having thus described my invention, I claim:

In combination with a duct, a cut off valve therefor, a normally open electric circuit, a solenoid mounted for sliding movement and included in said circuit, a gravity dog arranged in said circuit and adapted to be normally in contact with the solenoid, a circuit closing means connected with said duct and operable upon the diminution of the pressure of the gas therein to close said circuit, thereby energizing the solenoid to release the same from said dog, an arm connected with said cut off valve, and a link terminally connected with said arm and solenoid, whereby when said solenoid is released from the dog the cut off valve is drawn to a closed position.

In testimony whereof I affix my signature in presence of two witnesses.

ELMER JNO. HINKSON.
